(57) **CLAIM**

What is claimed is; the ornamental design for, a cover for a lawn mower, as shown and described.

DESCRIPTION

FIG. 1 is a first perspective view of a cover for a lawn mower, showing our new design;

FIG. 2 is a second perspective view thereof;

FIG. 3 is a third perspective view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a right side elevation view thereof; and,

FIG. 9 is a left side elevation view thereof.

The broken lines are for illustrative purposes only and form no part of the claimed design.
